(57) **CLAIM**

The ornamental design for: postcard form for maintaining privacy of information contained thereon, as shown and described.

DESCRIPTION

FIG. 1 is top view showing my new design for a postcard form for maintaining privacy of information contained thereon;

FIG. 2 is a view of the long side, the opposite side view being a mirror image thereof;

FIG. 3 is bottom view;

FIG. 4 is left side view of the short side; and,

FIG. 5 is right side view of the short side.

The broken lines in FIGS. 1 and 3 represent perforations for tearing. The central broken line in FIG. 3 also represents fold lines.
